(57) **CLAIM**

The ornamental design for a magnetic bar accessory holder, as shown and described.

DESCRIPTION

FIG. 1 is a front perspective view of a first embodiment of a magnetic bar accessory holder showing my new design;

FIG. 2 is a front view thereof;

FIG. 3 is a right side view thereof;

FIG. 4 is a rear view thereof;

FIG. 5 is a left side view thereof;

FIG. 6 is a top plan view thereof;

FIG. 7 is a perspective view of the first embodiment, shown attached to the arm of a user and holding a bottle opener and a pen;

FIG. 8 is a front perspective view of a second embodiment of a magnetic bar accessory holder showing my new design;

FIG. 9 is a front view thereof;

FIG. 10 is a right side view thereof;

FIG. 11 is a rear view thereof;

FIG. 12 is a left side view thereof;

FIG. 13 is a top plan view thereof; and,

FIG. 14 is a perspective view of the second embodiment, shown attached to the arm of a user and holding a bottle opener and pen.

Right side views not shown are mirror images of left side views. Bottom views not shown are mirror images of top views. Any broken lines illustrative of environmental structure in the drawings are not part of the design sought to be patented.
